UNITED STATES PATENT OFFICE.

FRANK J. REICHMANN, OF CHICAGO, ILLINOIS.

COIL AND STAND.

Application filed August 19, 1926. Serial No. 130,141.

This invention has to do with induction coils and particularly with the structural arrangements of such coils and the support or mounting therefor.

5 When designing induction coils, it must be borne in mind that the mounting means employed is very important. The mounting may have a very great effect upon the coil losses and the life of a coil is determined al-
10 most entirely by the manner in which the windings thereof are supported.

If the same electrical results are to be obtained while the coil is in use, it is necessary that the windings thereof be maintained 15 as nearly as possible in their original arrangement, for any mutilation thereof may have an effect upon the subsequent behavior of the coil. For this reason, the structural features should permit accuracy of manufacture and
20 assembly.

The objects of the present invention include the provision of an improved induction coil of the toroidal type, having unique structural characteristics and which is economical 25 to manufacture and which is not easily damaged, and a novel mounting therefor. Low loss in the coil is among the desirable characteristics attained.

In carrying out the invention, the toroidal 30 windings are supported around a dielectric core, which has its periphery shaped to engage the windings in intimate relation, the toroidal coil being preferably secured to this member by tying. A bifurcated mounting
35 member is secured in a slot in the dielectric core and supports portions of insulating material on which the terminals of the coil are supported.

The invention will be more fully understood 40 by a reading of following detailed description, considered with the accompanying drawing, in which:—

Figure 1 is an elevation of a coil embodying the main features of the invention, portions 45 thereof being broken away to illustrate some of the internal structure.

Figure 2 is a sectional view, taken on the line 2—2 of Figure 1 looking in the direction of the arrows.

50 Figure 3 is a view of the coil-supporting portions, looking from the angle at which the mounting member is secured to the coil supporting member.

Figure 4 is a plan view of one form of strip 55 for securing the primary within the secondary.

Reference should now be had to the accompanying drawing in which like reference characters are employed to designate similar members throughout the several views as well as in the description which follows.

The main coil supporting member is a core 10, of a dielectric, preferably of wood. To this is secured a bifurcated mounting member 11, generally secured in a slot in the member 10. A screw 12, or other fastening means may be employed for holding the core 10 and mounting member 11 together. The screw extends through an aperture provided for its passage in a transverse portion 11^a of the bifurcated member 11. This transverse portion is disposed between bifurcations which are designated by the reference characters 11^b and 11^c. A portion of each of the bifurcations 11^b and 11^c is turned at its end, 75 as illustrated particularly in Figures 2 and 3 to provide a base section for the mounting member. Apertures 13 are provided in said base portions and these may be utilized for the insertion of screws or the like to support 80 the coil upon any suitable base (not shown).

The windings of the coil as illustrated in Figure 1 are disposed around the exterior of the member 10. The windings comprise a primary 15 and a secondary 16. The secondary 16 is secured around the periphery of the member 10 by means of suitable strands 17, which are preferably tied in the open space 17' (Figure 1) between the ends of the windings of said secondary 16.

A cord of dielectric material 18 such as 90 cotton tape or the like, may be inserted within the convolutions of the secondary 16 before said secondary is placed about the member 10, and be used to secure said secondary upon the periphery of member 10. The material 18, as will appear obvious from a consideration of Figure 2, will be generally concealed by the secondary winding but it is desirable to have it of the same color as the insulation 100 upon the secondary 16.

The block or core 10 is provided with a V-shaped groove about its periphery. The convolutions of the secondary 16 are arranged as an uneven sided figure. Seven sides are 105 shown in the drawing. The windings of said secondary 16 are of the "hill and dale" type and succeeding convolutions are not in alignment except at the "points" or "angles" of the convolutions.

When the secondary 16 which is produced as a cylinder later bent to form a torus, one

of the "points" is made the innermost portion of the coil. These "points" are seated in the groove in the core 10. Cement may be used to keep the convolutions of secondary 16 in a fixed arrangement or definitely spaced after being seated upon said core 10. It is to be noted instantly, however, that the adjacent convolutions of the coil are contiguous at one "point" only. The contiguous portion is of the smallest compass conceivable. As a matter of fact, in seating the secondary 16, adjacent convolutions are caused to diverge outwardly from the center of their seat in the groove of core 10. This convergence further separates the convolutions and aids in preventing losses. Leakage across convolutions can occur only when adjacent convolutions are in proximity over an appreciable portion of their surface.

20 Within the secondary 16, the primary 15 should be disposed equidistant from the sides of the secondary coil 16. The convolutions in the primary 15 need not be of a "hill and dale" winding but should be regularly spaced. 25 A strip 19 of dielectric adhesively applied may be secured thereto at the innermost portion of said primary convolutions and on the inside thereof and extend longitudinally the shorter side of said coil 15 to provide one 30 form of a mounting therefor.

A retaining strip 20, preferably formed of a cellulose derivative, such as celluloid, extends around the exterior portion of the secondary winding 16 and has its two ends 35 cured together in a suitable manner at 21. The retaining strip 20 is arranged transversely of one of the flat sections of secondary 16 to grip the secondary windings in intimate relation, as shown in Figure 2, furnishing a 40 firm support therefor, but not extending over an appreciable area thereof. Cementitious binder may be used to hold the convolutions separate. After the retaining strip 20 is in place, it is usual to subject it to a solvent 45 therefor, which will have the effect of adhesively securing the contiguous portions of the convolutions thereto.

It is convenient to wind the coil portions 15 and 16 on mandrels. Within the secondary 50 16, a strip 20^a of dielectric may be placed. Celluloid may be employed. This strip is of such width that it seats itself parallel to the periphery of the core 10 and extends from the "point" in the coil adjacent the core and at 55 one side thereof to the "point" in said coil at its opposite side adjacent the periphery of said core 10. Accidental displacement of such a strip is not readily had in view of the depressions in the sides of the coil 16 which 60 tend to limit movement of said strip 20^a.

A special form of strip 120 is shown in Figure 4. This comprises a piece of dielectric having a tongue 121 and a groove 122 at its ends, and opposed tongues 123 intermediate its length. The strip end forming the

tongue 121 may be constricted to save material and to reduce the quantity of dielectric in the coil structure.

The primary 15 may be seated within the opposed tongues 123 and the leads to said primary 15 arranged to pass through the openings formed by cutting said tongues 123.

A secure seat for secondary 15 is thus obtained and its displacement prevented. An accurate gauge for positioning it within the secondary coil 16 is thus provided. Rapid assembly and avoidance of adhesives may also be obtained.

The primary 15 is then inserted within the secondary and the strands 17 threaded there-through.

The windings of secondary 16 are then brought around the periphery of the wooden supporting member 10.

The cord 18 on the inner surface of the secondary 16 is tightly tied in position. Necessary adhesive is applied at the lowermost "point" in coil 16. The strands 17 are finally tied in the position indicated in Figure 1. The peripheral surface of the supporting 90 member 10 is contoured as illustrated in Figures 2 and 3 so that the contiguous portions of the secondary winding 16 will be brought into intimate relationship therewith, thus forming a firm support.

When the retaining strip 20 is placed in position and adhesively attached to the coil 16, the windings thereof are very firmly held against damage.

Terminal supporting members 25 and 26 are secured to the bifurcations 11^b and 11^c respectively. Terminals 27, 28, 29, and 30 are secured to the terminal supporting members 25 and 26 as illustrated. The terminal supporting members 25 and 26 are preferably 105 of a nonconducting material such as fiber saturated with a phenol condensation product, since the mounting member 11 may be made of a mild steel or similar conducting material to obtain sufficient strength at a 110 very low cost.

As illustrated in Figure 1, the terminals are secured to their supporting members by eyelet rivets, and in securing the leads from the coils to the terminals, it is desirable to 115 employ an arrangement such as shown in Figure 1, in which the leads from the coils are brought through the eyelet, looped under the terminal extension and then soldered in the usual manner. This looping of the leads 120 practically negatives the possibility of having said leads accidentally disconnected from the terminals. As illustrated in Figures 1 and 2, it is preferable to extend the leads from the primary 15 to terminals 28 and 30, while the leads from the secondary winding are made to extend to terminals 27 and 29. Obviously, the leads may be arranged and received in other suitable manners.

It has been noted that the bifurcated 130

mounting member 11 is secured in a slot in the central coil supporting core 10. The reason for this type of mounting is to keep the supporting member out of the field of the coil since any conducting object which is projected into the field of the coil increases the power losses therein. Any other specific arrangement embodying this same principle can of course be used, but the best results are probably obtained with the specific construction shown.

A consideration of the design of the coil shows that there is relatively little extraneous protection for the coil. This is of very great advantage in cutting down the coil losses. One of the principal reasons why it is possible to get along with as little protection as is disclosed is that the "hill and dale" winding in itself provides considerable strength to a coil, and it is necessary to use only a narrow band thereof in the manner shown to obtain a rigid structure.

My invention, here disclosed, utilizes certain novel features which have heretofore been unknown in the art. In illustrating these novel features, it has been necessary to show a very specific article in order to make the improvements entirely clear. I do not wish, however, to be bound by the details of this present disclosure, and the invention is to be limited only by the scope of the appended claims.

Included in the advantages of this structure are an increased length of the primary, a smaller core, or coil hole, a larger second-

ary for the same diameter of transformer coil, a flat outer band for the coil.

What I claim as new and desire to secure by Letters Patent of the United States is:—

1. An induction coil comprising a toroidal secondary winding, a toroidal primary winding disposed therein, a coil supporting member, a bifurcated mounting member secured to the coil supporting member, a terminal supporting member of non-conducting material secured to each bifurcation, and a pair of terminals on each terminal supporting member, the leads from said primary and said secondary windings being secured to one portion of said terminals, and said terminals including means for securing outgoing leads thereto. 40

2. An induction coil as defined in claim 1, and wherein said toroidal secondary winding is of the hill and dale type. 50

3. An induction coil as defined in claim 1, and wherein said bifurcated mounting member is secured to said core supporting member outside of the field of said coils. 55

4. An induction coil comprising a toroidal winding, a central supporting member having its periphery formed to engage the toroid in intimate relation, a bifurcated mounting member secured to said supporting member, a terminal supporting member of non-conducting material secured to one of the bifurcations of said supporting member, and terminals secured to said terminal supporting member. 60 65
